(57) **CLAIM**

The ornamental design for a cordless phone and base, as shown and described.

DESCRIPTION

FIG. 1 is a right front perspective view of a cordless phone and base showing our new design;

FIG. 2 is a left rear perspective view thereof;

FIG. 3 is a rear elevational view of the handset portion;

FIG. 4 is a side elevational view of the handset;

FIG. 5 is a bottom end view of the handset;

FIG. 6 is a side elevational view of the base;

FIG. 7 is a top plan view of the base;

FIG. 8 is a rear elevational view of the base; and,

FIG. 9 is a bottom plan view of the base.

The base and handset are shown separately in FIGS. 3-9 for convenience of illustration.
